(57) **CLAIM**

The ornamental design for a candle burning furnace, as shown and described.

DESCRIPTION

FIG. 1 is a front and top perspective view of a candle burning furnace showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom perspective view thereof; and, FIG. 9 is an enlarged view of the candle burning furnace taken from the circle part in FIG. 1.

The broken lines circles in FIGS. 1 and 9 define the bounds of the enlargements and do not form part of the claimed design; the broken lines in FIG. 7 depict portions of the candle burning furnace that form no part of the claimed design.
